[57] CLAIM

The ornamental design for the electrical outlet strip, as shown and described.

DESCRIPTION

FIG. 1 is a perspective view of an electrical outlet strip according to the invention, illustrating the outlet covers moved to their closed position;

FIG. 2 is a top view of the electrical outlet strip of FIG. 1;
FIG. 3 is a left side view of the electrical outlet strip of FIG. 1;FIG. 4 is a bottom of the electrical outlet strip of FIG. 1;
FIG. 5 is a right side view of the electrical outlet strip of FIG. 1;FIG. 6 is a front view of the electrical outlet strip of FIG. 1;
FIG. 7 is a rear view of the electrical outlet strip of FIG. 1; and,

FIG. 8 is a top view of the electrical outlet strip of FIG. 1, illustrating the outlet covers moved to their open position. The broken line showing is included for the purpose of illustrating environmental structure only and forms no part of the claimed design.
